RADIO RECEIVING SYSTEM

Application filed October 3, 1927, Serial No. 223,762, and in France October 22, 1926.

My invention relates to an improved method and apparatus for receiving electric signal bearing waves, especially high frequency waves used for telegraphic and telephonic purposes.

It concerns more particularly the receiving method based on the use of beats between two waves and chiefly those of the superheterodyne type and the like. It is known that such methods are based on the changing of the frequency F of the incoming waves (which will be hereinafter termed primary frequency) into a frequency f , which will hereinafter be termed secondary frequency, which latter frequency is produced at the receiving station.

There are two main methods for changing the primary frequency into a secondary frequency f ; the first consists in producing and then detecting beats at secondary frequency due to the superposition of the incoming waves having a primary frequency F with a wave produced at the receiving station and having a frequency $F+f$, for instance. The second method consists in modulating at secondary frequency the currents at primary frequency received through the aerial (antenna or coil antenna) and in then detecting the primary current, thus modulated, in order to make the second frequency appear.

The first method provides a great sensitivity and a great selectivity, but it requires the tuning of two circuits to different frequencies viz: the tuning of the aerial to the frequency F and the tuning of the local circuit producing current at the frequency $F+f$.

According to the second method, the circuit producing modulating currents at the frequency f may be adjusted once and for all. Only the aerial circuit is to be tuned. However, the method does not allow any selectivity; any undesired wave at a frequency F' sufficiently near F to allow its reception through the aerial is transformed into a wave having a frequency f acting on the receiver; moreover, no heterodyne being used, the efficiency of the transformation is very small.

The method according to my invention combines the advantages of the preceding methods and allows the reception to be ob-

tained through one single adjustment, the sensibility and selectivity, however, being as high as in the receivers with two adjusting means.

It consists in modulating at the secondary frequency f (or at a frequency which is a multiple or a sub-multiple thereof) a current having a frequency equal to the primary frequency F and produced by a local generator, the current thus modulated being then superimposed on the incoming waves received by the aerial and the frequency of which it is desired to change in view of producing beats at the secondary frequency, these beats being finally detected so as to produce a current at secondary frequency, which, if desired, may be subsequently amplified.

The modulation of a frequency f or nf (n being an integer which may be equal to 1) of the local current provides currents having a frequency $F+nf$ and $F-nf$. When these currents are superimposed on the currents received through the aerial and having a frequency F , beats having the frequency nf are obtained, which beats may be detected so as to produce current at this same frequency nf .

Thus, the superimposition of the local wave and of the incoming waves produces beats or surges at secondary frequency just as in the superheterodyne method, whereby the sensitivity and selectivity of this method are retained. On the other hand, it is no longer necessary to provide for two adjustments since the oscillating circuits of the local generator and the receiving circuits must always remain tuned to the same frequency F of the incoming waves; it is easy to reach this result by giving to the inductances of both circuits equal values and by also giving to the capacities values always remaining equal to each other. A very simple form of execution consists in using inductance coils of unvariable value, which have been adjusted once for all, to give to the self induction of both circuits the same value, and in constituting the capacities by two similar adjustable condensers whose rotors are mounted on a common shaft actuated by a knob.

I have described hereinbelow by way of ex-

ample and shown on appended drawing a form of execution of my invention.

The apparatus is constituted by three vacuum tubes 1, 2, 3 each having a filament, grid, and plate, of the well-known type. The filaments are heated by the battery 13 whose current may be adjusted by the rheostat 14. The plates, or anodes, of the tubes 1 and 3 are polarized by the battery 15. The receiving circuit, constituted by a frame coil antenna 4, a primary coil 6, and an adjustable condenser 5, is inserted in the grid circuit of the vacuum tube 3, said grid circuit also including a grid leak comprising a condenser 16 and resistance 17, whereby the tube works as a detector or demodulator. An oscillatory circuit 10 is connected in the plate circuit of the detector 3 and is inductively coupled to an oscillatory circuit 11 connected to the input of the amplifier 12. These oscillatory circuits and the amplifier are tuned to the fixed secondary frequency.

The vacuum tube 1 is coupled and operated as a generator in an oscillating circuit, constituted by the inductance 18 and the condenser 19, inserted between the grid and the plate, one end of the filament being connected with a conveniently chosen point of the inductance 18, the plate of said tube being connected to the positive pole of the battery 15 through the intermediary of the choke coil 9. Between the plate and the oscillating circuit, is inserted the condenser 23 which prevents the battery 15 from being short-circuited by the inductances 9 and 18. The oscillating circuit 18-19 is adjusted once for all in such manner that the oscillations generated by the tube 1 have the fixed secondary frequency. The vacuum tube 2 is coupled to operate in the same manner, its oscillating circuit being constituted by the inductance 7 and the condenser 21; the plate 20 of said tube being connected, by the intermediary of the choke coil 8, to the plate circuit of tube 1; thus, the potential of the anode 20 is provided by the tube 1 and therefore oscillates at the fixed secondary frequency f . Between the plate 20 and the oscillating circuit 7, 21, a condenser 24 is provided, to prevent the short-circuiting of tube 2 by the oscillating circuit, and thus to prevent the oscillating currents generated by the tube 1 from passing by the inductance 7 instead of passing across tube 2. The oscillating circuit 7-21 is adjusted so as to produce, when there is no modulation current, oscillations at the frequency to which the receiving circuit 4-5 of the detecting tube is tuned.

This equality of adjustment is obtained by the fact that the self inductances of the coil 7 and of the receiving circuit 4, 6 have the same value and that the two condensers 5 and 21 are identical, the rotors being connected to each other and controlled by a single knob 22.

The inductance coils 6 and 7 may be adjustably coupled together. The choke coil 8 is adapted to prevent the high frequency oscillations generated by the tube 2 from passing into the circuit of the tube 1; while in the same manner the choke coil 9 prevents the oscillations generated by the tube 1 from passing into the circuit of the tube 2.

The generating tube 2, when it is modulated by the generating tube 1, no longer produces currents at a frequency F , but produces only current impulses interrupted each time the anode is brought to a negative voltage, the frequency of these impulses being $F+2f$ and $F-2f$. These currents produce induced currents in the circuit 4-5 by reason of the coupling 6-7 and therefore beats are produced in this circuit. Thus, after detection through the tube 3, there is produced in the anode circuit of the said tube three currents at a frequency $2f$ (60 kilocycles in the case of the example chosen), to which frequency the said anode circuit is tuned. This circuit is coupled with the circuit 11 tuned to the frequency $2f$ and connected with the amplifier 12 also tuned to the same frequency. The currents having a secondary frequency $2f$ are then either used directly or transformed by a further detection and, if required, a second heterodyning, into currents of low frequency.

The above described system is given only by way of example and it is possible without widening the scope of the invention to modify it for instance in the following manner.

It has been assumed that the secondary frequency is inaudible, but the method is applicable also when this frequency is audible.

With the connections shown, the superimposition of the waves having frequencies F , $F+2f$ and $F-2f$ is made in the circuit connecting the aerial with the tube 3, but it might be made in the anode circuit by any known and suitable anode modulating methods, the vacuum tube being provided, if required, with a second grid or anode.

The connections shown provide for the modulation at frequency f through the interruption of the current at a frequency F produced by the tube 2, but it is obvious that this modulation may be produced just as readily by connecting the anode of tube 2 to a suitable battery. This would afford a real modulation without any interruption of the anode current but the frequencies acting on the incoming waves would then be $F-f$, and $F+f$ instead of $F-2f$ and $F+2f$.

What I claim is:

1. The method of superheterodyne radio receiving, comprising tuning the antenna circuit to a given frequency, generating local oscillations at the frequency of the incoming oscillations, generating local oscillations at a secondary frequency, superimposing said

second local oscillations on said first-mentioned local oscillations, combining the composite oscillations thus produced and the incoming oscillations by demodulation, to produce a beat frequency and rendering audible the beat oscillations thus produced.

2. A radio receiver of the superheterodyne type comprising an adjustable receiving circuit, a first vacuum tube, an adjustable oscillatory circuit, means to connect said tube and said circuit in order to generate waves at the natural frequency of said circuit, common means to tune at the frequency of the incoming waves, said adjustable receiving circuit and said oscillatory circuit, a second generating tube, nonadjustable means to cause said tube to oscillate at a predetermined secondary frequency, means to modulate the waves generated by the first tube by the waves generated by the second one, means to superimpose said modulated waves on the incoming waves received by the receiving circuit, and means for detecting the beats produced thereby.

25 3. A radio receiver of the superheterodyne type comprising an adjustable receiving circuit, a first vacuum tube, an adjustable oscillatory circuit, means to connect said tube and said circuit in order to generate waves at the natural frequency of said circuit, means to give the same inductance to the receiving and oscillatory circuits, two similar adjustable condensers, a common shaft for the rotors of said condensers, a knob actuating said shaft, means to connect each condenser one in the receiving the other in the oscillatory circuit to cause their natural frequencies to keep always equal values, a second generating tube, nonadjustable means to cause said tube to oscillate at a predetermined secondary frequency, means to modulate the waves generated by the first tube by the waves generated by the second one, means to superimpose said modulated waves on the incoming waves received by the receiving circuit, and means for detecting the beats produced thereby.

50 4. A radio receiver of the superheterodyne type comprising an adjustable receiving circuit, a first vacuum tube, an adjustable oscillatory circuit, means to connect said tube and said circuit in order to generate waves at the natural frequency of said circuits, common means to tune at the frequency of the incoming waves said adjustable receiving circuit and said oscillatory circuit, a second generating tube, nonadjustable means to cause said tube to oscillate at a predetermined secondary frequency, means to feed the anode of the first vacuum tube by the current generated by the second tube, means to superimpose the modulated waves generated by the first tube on the incoming waves received

by the receiving circuit, and means for detecting the beats produced thereby.

In testimony whereof I have affixed my signature.
